UNITED STATES PATENT OFFICE.

JONATHAN A. HUNT, OF WESTBOROUGH, MASSACHUSETTS.

DESIGN FOR A SADDLE-POST.

SPECIFICATION forming part of Design No. 27,834, dated November 9, 1897.

Application filed September 25, 1897. Serial No. 653,059. Term of patent 7 years.

To all whom it may concern:

Be it known that I, JONATHAN A. HUNT, a citizen of the United States, residing at Westborough, in the county of Worcester and State of Massachusetts, have invented and produced a new and original Design for a Bicycle Saddle-Post and Cross-Piece, of which the following is a specification, reference being had to the accompanying drawings, forming a part thereof.

My invention relates to a bicycle saddle-post and cross-piece; and it consists in the new and original design for a bicycle saddle-post and cross-piece, as will be hereinafter fully described.

Referring to the drawings, Figure 1 is a side view of a post and cross-piece, showing my design, looking in the direction of arrow *a*, Fig. 2; and Fig. 2 is an end view looking in the direction of arrow *b*, Fig. 1.

The leading feature of my design for a bicycle saddle-post and cross-piece consists, in brief, of the tapering or wedge-shaped upper end of the tubular post, at its point of connection with the cross-piece, and the uniform diameter of the cross-piece throughout its length, and particularly the transverse diameter of the cross-piece in a horizontal plane directly over the post, being the same as the

diameter of the cross-piece in the same plane 30 at the front or rear thereof. By reason of the reduced width or diameter of the upper end of the tubular post, it is only in contact with the bottom of the cross-piece, thus leaving the cross-piece, at its point of connection with 35 said post, of uniform shape for nearly its full circumference, and of the same shape and diameter in cross-section as it is on either side of its point of connection with the top of the post.

In the drawings, 1 is the tubular post, which is of reduced width or diameter at its upper end and has the tapering or inclined surfaces 2, upon the upper end of which is secured the cross-piece 3, which extends at an angle to 45 the post 2. The cross-piece 2 at its point of connection with the upper end of the post 1 is of uniform shape for nearly its full circumference, as shown in Fig. 2.

What I claim is—

The design for a bicycle saddle-post and cross-piece, substantially as shown and described.

J. A. HUNT.
